UNITED STATES PATENT OFFICE

IRVING R. METCALF, OF ST. CHARLES, ILLINOIS, ASSIGNOR TO LATHAM MACHINERY COMPANY, A CORPORATION OF ILLINOIS

CONVERTIBLE TABLE FOR STITCHING MACHINES AND THE LIKE

Application filed December 31, 1928. Serial No. 329,655.

The present invention relates to a convertible table for use in connection with wire stitching machines or various other types of machines in which it may be desirable to have 5 the table in a horizontal position, or a portion thereof held in angular position with respect to another portion.

It has been found necessary, in connection with stitching machines, to provide two 10 forms of tables so that either flat work or pamphlet work may be stitched by the machine. These forms are used in connection with the stapling of flat work on the horizontal table, and stapling pamphlets accurately in the fold or crease of the pamphlet. Attempts have been made to form the table 15 in two sections with hinges between the sections, so that the horizontal table may be adjusted to an inverted V shaped table for 20 stitching pamphlets, but with this form, the hinges cause the inner edges of the inverted V shaped table to become separated at the apex and thereby permits inaccurate insertions of the staples in the pamphlets.

25 It is therefore the primary object of the present invention to not only eliminate the necessity of supplying two separate and distinct forms of tables with each machine, but to provide a convertible table of such form 30 in which the sections may be adjusted to accommodate flat work and pamphlets. In the present form, the inner edges of both sections forming the apex of the converted V shaped table contact, thereby insuring an accurate 35 insertion of the staples in the groove or seam of the pamphlet.

40 A further object of the invention is to provide a novel form of a linking lock arrangement which locks the table under the tension of a spring, in its normal horizontal position.

45 A further object of the invention is to provide a construction in combination with the convertible table which locks the sides or sections of the table when the table is adjusted for the accommodation of the pamphlets.

50 These and other objects are accomplished by providing a construction and an arrangement of the various parts in the manner hereinafter described and particularly pointed out in the appended claims.

Referring to the drawings, Fig. 1 is a side elevational view of the conventional form of stitching mechanism showing my improved form of convertible table mounted thereon.

Fig. 2 is a front elevational view of the construction of the supporting bracket and operating links. 55

Fig. 3 is a cross sectional view taken on the lines 3—3 in Fig. 2.

Fig. 4 is an end elevational view of the convertible table in its horizontal position, showing a portion thereof in cross section, and 60

Fig. 5 is an end elevational view showing the convertible table adjusted to a position in which the sections thereof are adjusted to the 65 position of an inverted V, for the accommodation of pamphlets.

In carrying out my invention, I have shown the same in connection with the conventional form of stitching machine which comprises 70 the usual main frame 10, stitching head 11 and clinching block supporting arm 12. Secured to the clinching block supporting arm 12, directly under the stapling mechanism by means of bolts 13 is a table supporting frame 75 or bracket 14. This bracket 14 is provided with two oppositely disposed downwardly extending portions 15, which in turn are provided with oppositely extending and outwardly projecting arms 16 and 17. The arms 16 project slightly further outwardly than the arms 17. Pivoted on the arms 16 by means of threaded studs 18 are links 19. Located on one side of the links 19 adjacent the pivotal connection at 18 is a laterally projecting lug 20 which is adapted to engage a stop 21 projecting on one side of the arms 16 and in the path of movement of the link 19. This lug is so arranged as to engage the lug 20 80 when the link is in its normal vertical position as shown in Fig. 4. In a similar manner a link 22 is pivoted through the medium of a threaded stud 23 to the arms 17. These links are similarly provided with laterally projecting lugs 24 which are adapted to engage stops 85 formed integrally with the arms 17 and laterally extending therefrom into the path of the movement of the links 22. All of these links 19 and 22 are provided with barrels or 90 bosses 26 located intermediate their ends and

95

100

106

on one side thereof. Reciprocally mounted in these barrels are spring press plungers 27 which are mounted in circular sockets 28 formed in the barrels. Mounted in the sockets 28 are compression springs 29 which have one of their ends thereof engaging the bottom of the sockets and the other of their ends engages the shoulder 30 of the plunger 27. The lower end of the plunger extends through an aperture 31 formed in the bottom of the barrels 25 and is provided with a cotter or pin 32 for securing the plungers from displacement from their respective barrels. The upper ends of the plungers are provided with large rectangular heads as shown at 33 and are adapted to engage the flat surfaces 34 formed on the lower side of the hinge brackets 35. The upper ends of the links 19 and 22 are pivotally connected to the hinge brackets 35 by means of pins 36. These hinge brackets 35 are secured to their respective table sections 37 and 38 by means of rivets 39. Located centrally of the respective table sections 37 and 38, and adjacent their contacting edges 43 is a cut-out portion as shown at 40, directly below which is located the clinching mechanism 41 shown in Figs. 2 and 4. This clinching mechanism is secured to the top side of the bracket 14 by means of screws 42. The inner edges of the table sections 37 and 38 are beveled at an angle as shown at 43 so that when the table is adjusted to an inverted V shape position as shown in Fig. 5 it will present a sharp apex forming a proper guide for engagement with the folded corner of the pamphlet to thereby insure the accurate positioning of the staples in the pamphlet. These pamphlets are fed over the inverted V shaped table under the stitching mechanism. Each of the arms 16 and 17 have outwardly extending beveled portions as shown at 44 which are adapted to engage the under side of the table sections adjacent the outer edges thereof so as to limit or stop the table sections and lock them in position when they are adjusted to that shown in Fig. 5.

In the operation of the above described device let us assume that the table is in a horizontal position or the position shown in Fig. 4 and the operator is desirous of converting the table so that it assumes an inverted V shape form or the form shown in Fig. 5, one of the sections 38, or preferably the outer edge thereof is depressed, swinging the brackets 35 about their pivots or pins 36 on the links 19, thereby forcing the plunger 27 against the pressure of the spring by reason of the flat side 34 of the bracket 35 pressing the head of the plunger 33 downwardly to a position in which the brackets 35 assume an angle equivalent to that shown in Fig. 5 with respect to their respective links 19, after which the table sections 38, brackets 35 and links 19 are swung inwardly about their pivots 18 until the under side of the table sec-

tion 38 contacts with the beveled projections 44 of the arms 16, in which the first section or section 38 assumes the angle shown in Fig. 5. In a similar manner the second section 37 is adjusted until it assumes a position 70 symmetrical to the first named section, after which the table then is adjusted to the position shown in Fig. 5, in which the tapered inner edges 43 of these table sections contact so as to form an accurately closed apex thereby insuring the folded portion of the pamphlets being properly guided over the clinching mechanism, so that the staples are accurately set in the folded edges of the pamphlet. 80

When the operator is desirous of opening or converting the table into a horizontal position, the reversed operation is necessary. That is, the links 19 and 22 are swung outwardly until the respective lugs 20 and 24 85 contact with the respective stops 21 and 25 thereby limiting or stopping the movement of these links in a vertical position. After this has been done the table sections 37 and 38 are then swung to a horizontal position and locked in this position by their respective spring press plungers 27 contacting with the flat edge 34 of the respective pivot brackets. 90

From the above description it will be seen that I have provided a simple, compact and economical construction of a convertible table in which, when the table is adjusted to assume an inverted V shaped form, that there is no open space at the apex thereby eliminating any possibility of the pamphlets being stapled off the folded edges. 95

While in the above specification I have disclosed one embodiment which my invention may assume in practice, it will of course be 105 understood that the same is capable of modification, and that modification may be made without departing from the spirit and scope of my invention as expressed in the following claims. 110

What I claim as my invention and desire to secure by Letters Patent is:

1. A convertible table for stitching machines and the like comprising a frame, links pivoted to said frame, table sections adjustably secured to said links, and means for adjusting said links and table sections with respect to said frame for angling said sections with respect to each other. 115

2. A convertible table for stitching machines and the like comprising a frame, table sections mounted on said frame, and means forming the connections between said sections and said frame whereby said sections may be adjusted to various angular positions with respect to each other and with respect to said frame so that the innermost edges of said sections are maintained in contact in all positions of adjustment. 125

3. A convertible table for stitching ma- 130

chines and the like comprising a frame, links pivoted to the opposite sides of said frame, hinged brackets pivotally secured to said links, and table sections secured to said hinge brackets whereby said sections may be adjusted to various angular positions with respect to each other.

4. A convertible table for stitching machines and the like comprising a frame adapted to be attached to the machine, links pivoted to said frame and adapted to be stopped in certain predetermined positions, hinged brackets pivoted to the free ends of said links and adapted to be locked with respect to said links in certain predetermined positions, and table sections secured to said hinge brackets whereby said sections may be adjusted to various angular positions with respect to each other.

20 5. A convertible table for stitching machines and the like comprising a frame, oppositely disposed pivoted links pivoted to said frame, means for stopping said links in a vertical position with respect to said frame, hinged brackets pivoted to the free ends of said links and means for locking said hinged brackets in substantially vertical alignment with said links, and table sections secured to said hinged brackets whereby said sections 25 may be adjusted to assume various angular positions with respect to each other.

6. A convertible table for stitching machines and the like comprising a frame, two movable sections operatively connected to said frame, and means for adjusting one section with respect to the other and for maintaining the inner edges of said sections in contact with each other so as to form a sharp apex at the point of contact.

40 7. A convertible table for stitching machines and the like comprising a frame adapted to be attached to the machine, links pivoted to the opposite ends of said frame, a lug formed on said link and adapted to engage a stop formed on said frame for stopping said links in a certain predetermined position with respect to said frame, hinged brackets pivoted to the free ends of said links, a spring pressed plunger carried by said links and adapted to engage said hinged brackets for frictionally locking said hinged brackets in various angular positions with respect to said links, and table sections secured to said hinged brackets whereby said table sections may be 45 adjusted in various angular positions with respect to each other so that the inner edges of said sections may be held in contact with each other in various positions of adjustment.

8. A convertible table for stitching machines and the like comprising a frame, table sections mounted on said frame, and movable connections between said table sections and said frame whereby said table sections may be adjusted from a horizontal position 55 to assume an inverted V shaped position in

which the apex thereof is sharp and pointed and at the same time maintain their inner edges in contact in either position.

In testimony whereof I have signed my name to this specification, on this 20th day ⁷⁰ of December A. D. 1928.

IRVING R. METCALF.
